CLAIM

The ornamental design for a toy top spinner, as shown and described.

DESCRIPTION

FIG. 1 is a top view of the toy top spinner showing my design;

FIG. 2 is a bottom view thereof;

FIG. 3 is a right side view thereof;

FIG. 4 is a left side view thereof;

FIG. 5 is a rear view thereof;

FIG. 6 is a front view thereof;

FIG. 7 is a top perspective view thereof; and,

FIG. 8 is a bottom perspective view thereof.

The broken lines shown in FIGS. 1 and 7 are for the purpose of illustrating a word that forms no part of the claimed design.

1 Claim, 4 Drawing Sheets
